T. Giesler Atty.

UNITED STATES PATENT OFFICE.

FRANK H. GILBERT, OF RIDGEFIELD, WASHINGTON.

SACK-HOLDER.

1,244,318.

Specification of Letters Patent. Patented Oct. 23, 1917.

Application filed November 2, 1916. Serial No. 129,210.

To all whom it may concern:

Be it known that I, FRANK H. GILBERT, a citizen of the United States, and a resident of Ridgefield, Clarke county, State of Washington, have invented a certain new and useful Improvement in Sack-Holders, of which the following is a specification.

The object of my invention is to provide a simple and efficient sack-holding mechanism especially such as would be suitable for use in connection with a hopper, and to so contrive such mechanism that the weight of the sack will be utilized to hold and lock the sack-suspending means in their proper holding position; at the same time so contriving the devices that they are controlled by a lever, the operation of which will place the holding mechanism in position to release the sack and thus permitting the latter 20 to pull itself loose by its own weight.

In order to attain my object my invention comprises certain structural features and combinations hereinafter fully described.

In the accompanying drawings:

Figure 1 is a front elevation of a hopper supported in any convenient way, and illustrates the manner in which my devices operate to hold the sack, and how the weight of the sack tends to securely hold my device 30 in its sack-holding position;

Fig. 2 is a side elevation of a hopper; and Figs. 3, 4 and 5 are details of construction.

The hopper, *a*, is supported by a supporting bracket *b*. At the sides of the hopper 35 are secured bearing brackets *c*, in the bent ends of which is journaled a shaft *d*. This shaft is provided with sack-holding prongs *e*, and an arm *f*, a corner *f'* of the latter being rounded, as shown, and provided with 40 an eye for attaching thereto the link *g*, which link supports a chain *g'*. The upper end of the chain is connected to a crank arm *h* of the shaft *i*, this shaft being journaled in brackets *j*. On the shaft *i* is a rigid handle 45 or operating lever *k*.

As shown in Fig. 2, the crank arms *h* of the shaft *i* are set at a slight angle with respect to the operating lever *k* so as to cause said arms to bear against the sides of the hopper *a*, in advance of the operating lever *k*. This causes the latter to stand free of the hopper so that it may be conveniently seized by the hand when it is desired to release the sack. The same arrangement incidentally serves another important purpose in that it places the extremity of the arms

h off center and causes the pull of the chain *g'* to throw and hold the crank arm *h* firmly against the hopper side, which effect is obtained by the weight of the sack and its contents, the sack being secured on the prongs *e*. A torsion spring *l* on the shaft *i* normally holds the crank arms *h* against the side of the hopper.

The end of the chain *g'* passes through a 65 dependent guide lug *m*, which is an integral part of the bracket *c*, and such lug is made with a D-shaped eye *n*, the straight side of which is so located as to be at right angles to the pull of the chain *g'*, in order to cause 70 the link *g* of said chain to come flat against said side, and thus cause the link to be properly positioned to perform its function.

As is to be seen from Fig. 1, when a weighted sack (represented by *s*) is suspended 75 from the prongs *e*, the downward pull on these prongs will cause the end of the arm *f* to exert a tug on the link *g*. By making the chain *g'* of just such length as shown in Fig. 1, with the crank arms *h* locked against 80 the hopper, the link *g* cannot be pulled through the eye *n* of the lug *m*, but will remain in approximately the position shown. The greater part of the upward force exerted by the arm *f* will be taken up by the 85 link *g* bearing against the upper part of the eye *n*. By this means very little stress is imposed upon the chain *g'*, thus doing away with the need of a heavy chain. The rounding of the corner *f'* enables the link *g'* to accommodate itself to the movement of the chain *g*. When the devices assume their sack-holding position, the upwardly inclined side of the eye *n* serves to guide the chain in such way as to re-position the link *g*, and thus again produce the locking effect. When the operating lever *k* is moved sufficiently 95 away from the hopper, the pull of the sack on the prongs *e* will further rotate the shaft *d* and cause the sack to pull off said prongs. 100 In such rocking of the shaft *d* the chain is readily pulled through the eye *n* of the lug *m*.

I claim:

1. In combination with a support, sack-holding means comprising a rock shaft provided with laterally projecting prongs, such shaft provided with an arm; a crank shaft provided with an arm and an operating lever, a flexible connection between the arm of said pronged shaft and the arm of said crank shaft, a guide for said flexible con-

nection, and said flexible connection including a link bearing in said guide when the sack-holding means are in their holding position, whereby the tendency of the pronged shaft to be rotated by the weight of the sack will cause said link of the flexible connection to bind with said guide.

2. In combination with a support, sack-holding means comprising parallel rock shafts provided with laterally projecting prongs, each of such shafts provided with an arm, a crank shaft, provided with arms and an operating lever, a flexible connection between the arms of said pronged shafts and 10 said crank shaft, a guide for said flexible connection, and said flexible connection including a link bearing in said guide when the sack-holding means are in their holding position, whereby the tendency of the pronged shaft to be rotated by the weight of the sack will cause said link of the flexible connection to bind with said guide.

3. In combination with a support, sack-holding means comprising parallel rock shafts provided with laterally projecting prongs, each of such shafts provided with an arm, a crank shaft, provided with arms and an operating lever, a flexible connection between the arms of said pronged shafts and 25 said crank shaft, a guide for said flexible

connection, such guide provided with a D-shaped eye the straight side of which is upwardly inclined, and said flexible connection including a link bearing in said eye of the guide when the sack-holding means are in 35 their holding position, whereby the tendency of the pronged shaft to be rotated by the weight of the sack will cause said link of the flexible connection to bind with said eye of said guide.

4. In combination with a support, sack-holding means comprising parallel rock shafts provided with laterally projecting prongs, each of such shafts provided with an arm, a crank shaft, provided with arms and 40 an operating lever, a flexible connection between the arms of said pronged shafts and said crank shaft, a guide for said flexible connection, said flexible connection including a link bearing in said guide when the sack-holding means are in their holding position, whereby the tendency of the pronged shaft to be rotated by the weight of the sack will cause said link of the flexible connection to bind with said guide; and the arm of said 45 crank shaft being set off center and at an angle with respect to the operating lever of the latter so as to bear against the support in advance of said operating lever.

FRANK H. GILBERT.
